COMBINATION COMB AND SHEATH HANDLE

Eugene J. Lux, New York, N. Y., assignor to
Columbia Protektosite Co., Inc., Carlstadt, N. J.,
a corporation of New Jersey

Application April 29, 1939, Serial No. 270,752

5 Claims. (Cl. 132—15)

This invention relates to combs and has particular reference to an improved combination comb and sheath handle.

One object of the invention is to provide a pocket comb device which shall not pick up dirt or other foreign substances nor have the teeth thereof subject to breakage when carried in the pocket.

Another object of the invention is to provide a device of the character described including a sheath and a comb, with the sheath coordinated in an improved manner with the comb so as to be adapted to constitute a handle therefor upon projection of the comb.

Another object of the invention is the provision of a device of the nature set forth comprising a comb and a sheath therefor having improved guide means spaced from the comb teeth for holding the comb in its projected position with the sheath forming a handle for the comb.

Another object of the invention is to construct a combination comb and sheath together with improved stop means limiting the sliding movement of the comb relative to the sheath, with the sheath forming a handle for the comb, all according to a simple, reliable, compact and inexpensive arrangement which is well adapted for quantity production.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in side elevation of a device embodying the invention, with the comb in retracted position in the sheath.

Fig. 2 is a view in end elevation thereof.

Fig. 3 is a sectional view taken on line 3—3 of Fig. 1.

Fig. 4 is a view of the device with the comb in projected position and parts removed to show a stop means.

Fig. 5 is a side view of the comb in detached position.

Fig. 6 is a bottom edge view of the comb.

Fig. 7 is a fragmentary view in side elevation of a modified form of the invention showing a different stop means.

Fig. 8 is an end view thereof.

Fig. 9 is a fragmentary horizontal sectional view of a device according to the invention showing a different stop means.

Fig. 10 shows the device of Fig. 9 with the stop means in course of being moved to operative position in assembling the comb and sheath.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device embodying the invention. The same 20 may include a hair comb 11 and a sheath 12 therefor. The latter may be of thin flat tubular form desirably open at its opposite ends. More specifically, the sheath 12 may have longitudinal edge walls 13, 13a and side walls 14, extending 25 continuously from end to end of the sheath.

The comb 11 may have the usual teeth 15, extending from a back 16. At one end of the comb is a finger piece or loop 17 for causing movement of the comb.

When not in use, the comb 11 is fully housed in the sheath, except that the finger piece 17 projects therefrom as shown in Fig. 1. In normal use, a substantial part of the comb body projects from the sheath, as shown in Fig. 4, except that 35 a portion of the comb remains in the sheath in engagement therewith so that the sheath constitutes an extension or handle for the comb to facilitate the use thereof.

These retracted and projected positions of the 40 comb 11 are effected by sliding movement of the comb in the sheath 12 in the longitudinal direction through an end opening of the sheath. Since the flexibility of the comb teeth does not permit them to function as a nonbreakable guide 45 means for the sliding action and for the rigid, reliable holding of the comb in its projected position, the invention provides a different means for this purpose.

Accordingly, the comb back 16 may comprise a 50 rail or track portion 18 extending substantially from end to end of the comb. Guidingly engaging the rail 18 is a tubular element 19 forming a part of the sheath and engaging the rail at the top, bottom and sides thereof, so that the 55

comb may act as if suspended from the positive track means 18, 19. Hence the teeth 15 need not engage nor accidentally abut the sheath, with consequent breakage of teeth when the comb is forcibly slid along the sheath, and furthermore, the track means holds the comb quite rigid in its projected position. The section 19 may be regarded as a split tube communicating with the interior of the rest of the sheath, or it may be considered as an undercut guide.

If a reenforcing securement of the comb 11 be desired, the latter may have an end portion 20, opposite to the finger piece 17, said end portion 20 forming an uninterrupted plate section whose bottom edge 21 may have snug guiding engagement with the bottom wall 13a of the sheath. Thus a guiding holding action to supplement that of the track means 18, 19 is afforded, especially when the comb is in projected position, and any tendency of the comb to move angularly and to become loose under stress is counteracted.

For limiting the movement of the comb between projected and retracted positions, suitable stop means may be provided. For example, the plate section 20 may be downwardly extended so that its bottom edge 21 lies below the lower end of the teeth 15 to thus constitute the part at 21 a stop portion. The latter may be engageable with an internal upraised stop portion 22 in the sheath formed, for instance, on the bottom wall 13a. Thus a concealed stop means 21, 22 limits the movement of the comb toward its projected position.

To limit the movement of the comb 11 toward its retracted position, stop projections 23 may be formed at the finger piece 17 at opposite sides of the comb adapted to abut an adjacent end edge of the sheath 12. If desired, the side walls 14a of a modified sheath shown in Fig. 7 may be internally undercut as at 24 to receive the stops 23 so that the latter are in concealed position.

In order to prevent the comb 11 from accidentally moving outward from its retracted position, stop portions or projections 25 may be provided on the plate section 21. These stop portions 25 are of less height than the stop portions 23, and are adapted to readily move into the sheath with a frictional wiping contact with the side walls of the sheath when the comb is moved to projected position.

According to Figs. 9 and 10, a modified construction includes the sheath side walls 14b, and the comb 11a having certain teeth 15a thereof provided with stop projections at opposite sides of the comb, the adjacent ends of the sheath being offset as at 27, 28 for abutment with both stop projections simultaneously. In Fig. 10, the teeth 15a are shown resiliently deflected by the projections 26 as the same are forced into the sheath in course of assembling the comb therewith.

With the present invention, each of the comb and sheath sections may be a one-piece structure, made, for instance, of molded plastic; and this applies to all forms of the device, each embodying the same broad principles and being adapted for use and for assembling in the same manner.

More particularly, the device 10 may be assembled by forcing the comb into the sheath with the finger piece 17 leading. The stop portions 23 tend to resiliently spread the side walls 14 of the sheath, whereby the comb and sheath are permanently operatively interconnected in a simple manner.

By reason of the fact that the sheath is open at both ends, the strong plate section 20 may be used as a stop at 21, as well as a guide, and powerfully resists any stress tending to separate the comb from the sheath when the comb is in use. 5

Because of the tubular construction of the sheath it forms a rugged handle for the comb; and the track means 18, 19 assures reliable mounting of the comb and avoids breaking of the teeth thereof.

10

I claim:

1. A combination hair comb and sheath handle therefor, comprising a hair comb, and an elongated sheath of flat tubular form permanently closed along its sides and longitudinal edges, said sheath consisting of relatively rigid material and being permanently fully open at its opposite ends, said comb being longitudinally slideable into and outward of the sheath through an end opening of the latter, a finger piece at one end of the comb for manual outward movement thereof, stop means limiting insertion of the comb into the sheath so that said finger piece normally projects from the sheath, and other stop means limiting withdrawal of the comb so that a substantial portion of the comb remains in the sheath, said portion of the comb and the sheath having snug interfitting engagement with each other so that said sheath is adapted to constitute a handle for relatively rigidly holding the comb in the outward operative position thereof.

2. A combination hair comb and sheath handle, comprising a hair comb having a back having a longitudinal rail of greater width than the comb, a sheath in which said comb is longitudinally slideable into housed position in the sheath and into operative position with a substantial portion of the comb lying outside of the sheath, said sheath having a portion having a longitudinally undercut groove to snugly slidably receive said rail and having guiding engagement with the rail at the top, sides and bottom thereof to thus rigidly hold the comb in its operative position with the teeth of the comb being relatively free of the sheath.

3. A combination hair comb and sheath handle therefor, comprising a hair comb, and an elongated sheath of flat tubular form permanently closed along its sides and longitudinal edges, said sheath consisting of relatively rigid material and being permanently fully open at its opposite ends, said comb being longitudinally slideable into and outward of the sheath through an end opening of the latter, a finger piece at one end of the comb for manual outward movement thereof, stop means limiting insertion of the comb into the sheath so that said finger piece normally projects from the sheath, and other stop means limiting withdrawal of the comb so that a substantial portion of the comb remains in the sheath, said portion of the comb and the sheath having snug interfitting engagement with each other so that said sheath is adapted to constitute a handle for relatively rigidly holding the comb in the outward operative position thereof, the first mentioned stop means being integral with the comb and being a projection at a side of the comb, the second mentioned stop means including portions integral with the comb and sheath, said sheath being slightly resiliently expandable by the said projection on forcibly inserting the comb into the sheath so that said projection is passed through the sheath, said projection being at the finger piece end of the comb and being 75

adapted to abut an adjacent end of the sheath. 4. A combination hair comb and sheath handle therefor, comprising a hair comb, and an elongated sheath of flat tubular form permanently closed along its sides and longitudinal edges, said sheath consisting of relatively rigid material and being permanently fully open at its opposite ends, said comb being longitudinally slidible into and outward of the sheath through an end opening of the latter, a finger piece at one end of the comb for manual outward movement thereof, stop means limiting insertion of the comb into the sheath so that said finger piece normally projects from the sheath, and other stop means limiting withdrawal of the comb so that a substantial portion of the comb remains in the sheath, said portion of the comb and the sheath having snug interfitting engagement with each other so that said sheath is adapted to constitute a handle for relatively rigidly holding the comb in the outward operative position thereof, the first mentioned stop means being integral with the comb and being a projection at a side of the comb, the second mentioned stop means including portions integral with the comb and sheath, one of said portions being located at an edge of the comb and the other of said portions being a raised step within the sheath at an edge thereof, said sheath being slightly resiliently expansible by the said projection on forcibly inserting the comb into the sheath so that said projection is passed through the sheath, said pro-

jection being at the finger piece end of the comb and being adapted to abut an adjacent end of the sheath.

5. A combination hair comb and sheath handle therefor, comprising a hair comb, and an elongated sheath of flat tubular form permanently closed along its sides and longitudinal edges, said sheath consisting of relatively rigid material and being permanently fully open at its opposite ends, said comb being longitudinally slidible into and outward of the sheath through an end opening of the latter, a finger piece at one end of the comb for manual outward movement thereof, stop means limiting insertion of the comb into the sheath so that said finger piece normally projects from the sheath, and other stop means limiting withdrawal of the comb so that a substantial portion of the comb remains in the sheath, said portion of the comb and the sheath having snug interfitting engagement with each other so that said sheath is adapted to constitute a handle for relatively rigidly holding the comb in the outward operative position thereof, said comb having a back having a longitudinally extending rail of substantially greater width than the comb, said sheath having a portion having a longitudinally undercut groove to snugly slidingly receive said rail along the top, sides and bottom of the latter to thus rigidly hold the comb in its withdrawn position, and the teeth of the comb being relatively free of the sheath.
